UNITED STATES PATENT OFFICE.

WILLIS G. VAN AUKEN, OF SAGINAW, MICHIGAN.

DESIGN FOR A MATCH-SAFE.

SPECIFICATION forming part of Design No. 29,818, dated December 20, 1898.

Application filed August 15, 1898. Serial No. 688,651. Term of patent 14 years.

To all whom it may concern:

Be it known that I, WILLIS G. VAN AUKEN, a citizen of the United States, residing in the city and county of Saginaw, State of Michigan, 5 have invented and produced a new and original Design for Match-Safes, of which the following is a specification, reference being had to the accompanying drawings, forming a part thereof.

- Figure 1 is an elevation of the match-safe. Fig. 2 is an end view of Fig. 1.

As shown in the drawings, the leading feature of my design consists of the plate A, having upon its surface the match-holder B and the cup at the side of the match-holder, 15 as shown in Fig. 1.

Having thus described my invention, what I claim as new, and desire to secure by Letters Patent, is—

The design for a match-safe, as herein shown 20 and described.
